UNITED STATES PATENT OFFICE

JEAN SWICKY, OF FARNHAM ROYAL, ENGLAND

FILLING NOZZLE

Application filed April 28, 1928, Serial No. 273,678, and in Great Britain March 8, 1928.

This invention relates to filling nozzles such as are commonly employed at the end of a flexible hose for supplying gasoline to the tanks of automobiles and aircraft. The 5 invention is particularly concerned with nozzles which embody a removable filter and a valve.

The purposes of the invention are to cheapen the manufacture of such nozzles by 10 eliminating or minimizing machining operations, and by simplifying the assembly of the nozzle; to provide a nozzle which will remain in working order for a long time under adverse conditions; and one which 15 can be taken to pieces for cleaning and re-assembled without the use of tools. The last-named purposes arise from the necessity of equipping re-filling stations, especially for aircraft, in remote districts, under widely 20 different and often severe climatic conditions, and far removed from even the simplest engineering resources.

With these purposes in view I have devised the construction of filling nozzle illustrated by the accompanying drawings and possessing the novel features described hereinafter and defined in the appended claims.

In the drawings,

Figures 1 and 2 show views at right angles 30 mainly in axial section of an embodiment of the invention,

Figure 3 shows a modification of detail.

The principal component of the nozzle, herein termed the filter body, is a casing consisting of two cylindrical portions 1, 2 each open at both ends. The axes of the cylinders are at right angles but do not intersect, the cylinders having a common diameter. The 35 cylinder 1 receives the filter and the cylinder 2 the valve, and this relative disposition of the two cylinders makes possible considerable simplification in the attachment or fastening of both filter and valve.

The cylinder 1 has a threaded end 3 serving for the attachment of a hose, and constituting the inlet of the nozzle. Near this end there is a collar 4 within the cylinder, and a similar collar 5 is formed at the other end of the body.

The removable filter comprises a skeleton

frame upon which are stretched in cylindrical form a series of sheets 6 of perforated metal and wire gauze of increasing fineness. The skeleton frame is made up of an end plate 7, an end ring 8, and longitudinal members 9 joining the plate and ring. The sheets 6 rest on the reduced inner ends of the plate and ring respectively and their straight edges meet and are fastened upon one of the members 9. The larger part of the ring 8 closely fits the collar 4, the fit being so close as not to permit the passage of any particle which would be retained by the finest of the gauze sheets 6. The end plate 7 has a cylindrical surface fitting the collar 5 but so close a fit as between 8 and 4 is not here necessary. The end plate has also a recessed flange 10 projecting over the edge of the body 1. In the recess is a washer or packing ring 11 which makes a fluid-tight joint with the body, and being held in the recess cannot expand or spread laterally under the pressure applied to it. From the middle of the plate 7 there projects a threaded boss 12. To facilitate entering the filter into the closely fitting body the edge of ring 8 is bevelled and webs 13 are formed in the body having inclined edges leading to the collar 4.

The filter is fastened in position by a cap 14 which screws upon the body 1, bears upon the flange 10 of the end plate 7, and has a central part 15 surrounding the boss 12. A nut 16 screwed and pinned upon the boss 12 permanently unites the cap and the end plate, and causes the filter to be positively withdrawn from the body when the cap is unscrewed.

The filter separates the inlet 3 from the portion 2 of the filter body. One end of the portion 2 is closed by a screwed cap 17 which is recessed to receive packing and a gland 18. To the other end of the portion 2 is attached a suitable delivery device, consisting, in the construction shown, of a screwed connector 19 which holds in place a rain shield 20 and receives a delivery pipe 21, the end of which may be covered when not in use by a cap 22 chained to the body. This delivery may be unscrewed and replaced by a different form to suit particular pur-

poses, for instance by a delivery which will screw upon the flange of a gasoline tank.

Through the gland passes the stem 23 of a valve 24 seating upon the connector 19 at the end of the chamber 2. The valve is made with an undercut recess 25 in the wall of which is cut away on one side, and the stem 23 is made with a groove 26. The end of the stem can be entered sideways into the valve and is retained by a sleeve 27 fitting over it. A spring 28 compressed between the sleeve 27 and the gland 18 serves both to press the valve upon its seat and to keep the gland packing tight. An additional sleeve or distance piece 29 shorter than the distance between 18 and 27 by the desired lift of the valve prevents the spring 28 being unduly compressed.

For the purpose of operating the valve the stem is formed in Figures 1 and 2 with a thread 30 fitting a corresponding thread in the cap 17, and outside the cap the stem carries a handle or head 31 by which it may be turned. In small nozzles the alternative construction shown in Figure 3 may be adopted, the stem 23 there having no thread, but having pivoted to it outside the cap 17 a lever 32 the end 33 of which acts as a cam or eccentric bearing upon the cap when the lever is turned to the position shown in dotted lines so that the valve is lifted.

All the screw threads upon the device may be made of the same pitch. The cap 14 can be turned by hand without the aid of tools, being suitably shaped to give a good grip. By its aid the filter may be readily withdrawn for cleaning and as readily replaced. There is no part that can be detached and lost, and no possibility of assembling the nozzle with no filter in position. The valve 24 can adjust itself to its seating so as always to make a good joint; and wear on the gland packing is automatically taken up without attention. By means of these features and others above described the merits of which it is unnecessary to set out at length the device is adapted to withstand long wear without attention, and is readily handled and cleaned without the use of tools.

What I claim is:

1. A filling nozzle comprising a one-piece cylindrical filter body, having a lateral extension, a filter having a closed end, closing one end of said body and separating the other from the lateral extension, a valve in said lateral extension, a threaded boss on the end of said filter, a cap screwing upon said body and pressing said filter into place, said boss projecting through said cap, and a nut upon said boss outside the cap.

2. A filling nozzle comprising a one-piece body consisting of two interpenetrating cylindrical portions open at their ends, said cylinders having their axes at right angles, a

removable filter fitting one of said portions closing one of its ends and separating the open end from the second portion, means for retaining said filter in position, a cap closing one end of the second portion containing a gland, and a valve having its stem passing through said gland and seating upon the other end of said second portion.

3. A one-piece filling nozzle comprising a filter body formed of two cylindrical portions having their axes at right angles and not intersecting, said two portions opening one into the other intermediate the ends of each, a filter closed at one end making joint with both ends of the first portion, a cap closing one end of the second portion, a gland in said cap, a valve closing the other end of the second portion having its stem passing through said cap, and a spring compressed between said gland and said valve.

In testimony whereof I have signed my name to this specification.

JEAN ZWICKY.
